APPARATUS FOR TESTING AND
ADJUSTING CARBURETORS

Howard D. Green, Atlantic, Mass.

Application December 24, 1934, Serial No. 758,894

7 Claims. (CL 73—51)

This invention relates to a device for testing and adjusting carburetors for internal combustion engines, and for visually indicating the rate of fuel consumption by an internal combustion engine.

Carburetors as commonly constructed utilize the suction action of the engine to draw air past the fuel inlet nozzle so as to form an explosive mixture that is drawn into the cylinders. The efficiency with which an engine operates and the amount of fuel it consumes therefore depends to a considerable degree upon the strength of the suction produced in the manifold of the engine.

Therefore in tuning up an engine and adjusting the carburetor it is important to determine whether or not the suction produced by the engine is proper, and if the suction is defective it should be corrected before attempting to secure the final adjustment of the carburetor.

Heretofore in many cases the adjustment of carburetors has been largely a matter of guess work without accurate knowledge being had as to the degree of vacuum produced in the engine manifold or the rate of fuel consumption by the carburetor for different engine speeds.

The present invention therefore contemplates a device for use in securing the proper adjustment of an engine carburetor to obtain maximum power and minimum fuel consumption, and its use consists in first determining by vacuum readings the suction action produced in the engine intake manifold, correcting as far as feasible any defects in the engine operation indicated by the vacuum readings, then visually determining the rate of flow of fuel to the carburetor and adjusting the carburetor to secure the lowest fuel consumption obtainable at one or more speeds for the particular suction action of this engine.

One important feature of the present invention resides in an indicating device constructed to give vacuum readings showing the suction produced in the engine manifold, and to give a clear and continuous showing of the rate at which fuel is being consumed by the carburetor at different engine speeds and for different carburetor adjustments.

A more specific feature resides in an indicating device provided with a pair of sight tubes, one being graduated for use in testing the carburetors of engines in small or average size automobiles and the other for testing the carburetors of larger engines such as used in trucks and busses, and provided with a constant level chamber for supplying fuel to these tubes through calibrated ori-fices so that the rate at which fuel enters these

tubes will vary with the head pressure or the level of the fuel in a tube below that of the fuel in the constant level chamber.

A further feature resides in the valve arrangement for placing one or the other of these tubes in operation to supply an indicated flow of fuel to the carburetor being tested, and in the construction and arrangement whereby the carburetor may be tested without resorting to a road test.

Still a further feature resides in the construction and arrangement whereby the adjustment of the control valve to a position to take a reading from either one of the tubes causes the other tube to fill rapidly in readiness for the taking of a reading therefrom. In this manner an intimate cooperation between the control valve and the two sight tubes is obtained whereby the filling of one is secured while the other is being emptied.

Other features of the invention and novel combination of parts in addition to the above will be hereinafter described in connection with the accompanying drawing which illustrates one good, practical form thereof.

In the drawing:

Fig. 1 is a front elevation of a box or casing provided with the indicating mechanism of the present invention.

Fig. 2 is an elevation of the rear face of the door of the box of Fig. 1 showing the mechanism mounted thereupon.

Fig. 3 is a sectional view taken on the line 3—3 of Fig. 1.

Fig. 4 is a diagrammatic view of a valve and calibrated apertured connections to be described; and

Fig. 5 is a diagrammatic view showing the present testing device in use.

The testing device of the present invention is designed for use primarily by automobile repair men and is therefore shown as mounted in a portable box or casing conveniently formed of wood, and having a door or front wall 10 which is secured by hinges 11 to a side wall 12 of the box having the rear wall 13, and a fastener 14 serves to hold the door closed.

The door 10 is shown as having a hole formed therein of a size to snugly receive a vacuum gage 15 for testing the engine. This gage may be of well known construction and adapted to give vacuum readings from say 1 to 30 inches of mercury. The face of the gage dial, however, is especially marked, as will be hereinafter described, to facilitate testing and adjusting the engine. The gage 15 has a needle 16 that travels over the

face of the dial and the gage casing may have the usual threaded nipple 17 that is shown as secured to a bracket 18. This bracket is secured by screws to the rear face of the door 10, and a tube 19 projecting from the bracket leads to the interior of the gage.

In the embodiment of the invention shown the carburetor testing device is provided with two sight tubes for use in indicating the rate of fuel consumption. One tube 20 is designed for use in testing carburetors for the smaller and average size automobiles and the other tube 21 is designed for use in testing larger carburetors such as employed on trucks and busses. The tube 20 is provided with a scale 22 which as shown is graduated to indicate a gasoline consumption from "0" to "1.15" gallons per hour, and the tube 21 is provided with a scale 23 which is provided to indicate a gasoline consumption from "0" to "2.7" gallons per hour. The tubes 20 and 21 are preferably mounted in grooves formed in the face of the door 10 as will be apparent from Fig. 3.

Upon the inner face of the door 10, in the construction shown, is mounted a constant level supply casing 24, which may be of well known construction, and has a valve stem 25 secured to a float valve lever 26 pivoted at 27 and provided with the float 28. The arrangement is such that the gasoline or other fuel will remain at a constant level in the casing 24 which may have the cover 29.

Provision is made for supplying the fuel from the casing 24 to the glass tubes 20 and 21 so that it may rise in these tubes to the level of the fuel in the casing 24, and to this end, in the construction shown, a pipe 30 is provided at the rear of the door 10 and extends downwardly from the casing 24 to near the lower end of the tubes 20 and 21. The pipe 30 preferably has an air vent tube 31 extending upwardly above the level of the fuel in the casing 24, and the upper ends of the tubes 20 and 21 are vented.

In the construction shown the lower end portion of the tube 20 is connected with the pipe 30 by the laterally extending pipe 32 and by a by-pass pipe 33, and the tube 21 is similarly connected with the pipe 30 by the laterally extending pipe 34 and by-pass pipe 35, so that each tube 20 and 21 has two lateral connections with the fuel supply pipe 30. The coupling 36 for the pipe 33 is preferably provided with a small calibrated orifice adapted to retard the flow of fuel from the pipe 30 to the tube 20 through the by-pass pipe 33, and the coupling 37 has a larger calibrated orifice that serves to retard the flow of fuel from the pipe 30 to the tube 21 through the by-pass pipe 35.

A valve casing 38 serves to connect the lower end of the pipe 30 to the laterally extending pipes 32 and 34 and the flow of fuel from the pipe 30 to the pipe 32 or 34 is controlled by the rotating valve 39 as will be apparent from Fig. 4. When the valve 39 which has a pointer 40 is turned to the position marked "Small motors" (see Fig. 1) the pipe 34 leading to the tube 21 will be connected with the supply pipe 30, and the pipe 32 leading from the tube 20 will be connected with the discharge pipe 41 extending downwardly from the valve casing 38. If the valve 39 is turned to the position marked "Large motors" fuel will be supplied to the tube 20 from the pipe 30 through the pipe 32 and will be permitted to flow from the tube 20 through the pipe 34 to the discharge pipe 41 as will be apparent from Fig. 4 in which S indicates the "small motors" position and M the

"large motors" position. When the valve is turned to the intermediate position marked "Closed" both pipes 32 and 34 are cut off from pipe 30 and the discharge pipe 41 is cut off from pipes 32 and 34, as will be apparent from Fig. 4. 5

When it is desired to employ the testing device of the present invention to test and adjust the carburetor of an engine such, for example, as an automobile engine, the wood box or casing 10, 12, 13 may be supported from a post or otherwise near 10 the automobile engine, and the vacuum gage 15 may then be connected with the intake manifold 42 of an internal combustion engine 43 by a rubber tube or the like 44 leading from the manifold to the tube 19. 15

The usual pipe connection 45 leading from the automobile fuel supply tank 46 to the engine carburetor 47 may be disconnected and the tank 46 is connected with the constant level casing 24 of the present device by a flexible pipe 48, so that 20 the usual fuel pumping means (not shown) will feed the fuel from the tank 46 to the casing 24. This casing should be supported at a sufficient height above the level of the carburetor 47 to secure a gravity feed through the pipe 49 from 25 the valve casing 38 to the carburetor 47.

The testing device of the present invention is now ready for taking readings and one or both rear wheels of the automobile may be jacked up and the engine started so that the automobile 30 speedometer will show the speed. Reading may now be taken upon the vacuum gage 15 to determine if the engine is operating correctly and produces the desired suction in the engine manifold 42. If the vacuum gage shows the engine defective in this respect the necessary corrections should be made, for example, by correcting the action of the engine valves, piston rings, spark gaps or timing mechanism. 35

After these corrections have been made as completely as the general condition of the automobile or other controlling condition may warrant, then the carburetor should be tested and adjusted to secure the lowest fuel consumption, as indicated in the sight tube 20 or 21, that can be obtained 45 for the suction action of this particular engine at different speeds.

When the float casing 24 of the present device is supplied with fuel and the valve 39 is turned to the closed position fuel will flow through the 50 pipe 30 and by-pass pipes 33 and 35 into the tubes 20 and 21 to rise slowly therein to the level of the fuel in the casing 24. Now if the valve 39 is turned to the "small motors" position, and the motor is started, the fuel will remain at the zero 55 point near the top of the tube 21, but will fall in the tube 20 as the fuel feeds from this tube to the carburetor, until it comes to rest at the graduation say "1.05" which will indicate the rate at which the fuel is being consumed by the carburetor at a particular speed. If the carburetor is then adjusted to require less fuel this will be promptly shown by the rising of the fuel in the tube 20 to a position say "95", which shows the fuel saved by the better carburetor adjustment. 65 If the tube 20 will not supply the fuel to the carburetor fast enough, then the valve 39 is turned to the "large motors" position to supply fuel to the carburetor from the tube 21 having the larger calibrated orifice 37. 70

It will be understood that the rate at which fuel is supplied to the tube 20 or 21 through the calibrated orifice 36 or 37 varies with the head pressure, and when the fuel level falls in one of these tubes the rate at which the fuel passes 75

through the calibrated orifice increases, substantially in proportion to the square root of the head pressure until it equals the carburetor consumption at that time, which is shown by the height 5 of the fuel in this tube.

It will therefore be seen that by employing the carburetor testing device of the present invention the amount of gasoline being consumed by the engine at different speeds and for different carburetor adjustments is readily determined by 10 noting the height of the gasoline in the tube 20 or 21 being used and the reading of the scale at this height.

Since the by-pass pipes 33 and 35 are provided 15 with the small calibrated orifices 36 and 37 respectively, the tubes 20 and 21 will fill slowly through these by-passes. It is, therefore, desirable to provide means whereby either tube may be filled quickly ready for a reading and also 20 whereby one tube may be quickly filled while the other tube is being used in testing the engine. This is accomplished by employing the valve construction shown which operates to establish a connection between the tube 30 and one pipe 32 25 or 34 when the other pipe is connected with the discharge pipe 41.

When an engine is being tested by taking vacuum readings these readings give definite indication 30 of certain engine defects, and it is helpful to mark the vacuum gage dial to clearly show the significance of certain readings. For example, when the reading lies in the black section marked *a* a leaky intake gasket is indicated; when the reading lies in the black section indicated by *b* late valve timing is indicated; when the reading lies in the black section indicated by *c* late ignition timing is indicated; and when the reading lies in the black section indicated by *d* proper 35 or normal motor conditions are shown.

40 I claim:—

1. A device for determining the rate at which fuel is consumed by an internal combustion engine, comprising in combination a pair of sight tubes, a constant level supply chamber connected 45 to the sight tubes, a discharge conduit connected with said tubes to discharge the fuel from either tube at a common point, a by-pass connection provided between said supply chamber and each tube, a calibrated orifice in one by-pass and a larger calibrated orifice in the other by-pass, and 50 means associated with said connecting discharge conduit for placing one tube or the other in operation to determine the rate of fuel consumption and also operable to fill the other tube from said supply chamber.

2. A device for determining the rate at which fuel is consumed by an internal combustion engine, comprising in combination a pair of sight tubes, a constant level supply chamber, a discharge conduit connected with said tubes to discharge the fuel from either tube at a common point, a by-pass connection provided between said supply chamber and each tube, a calibrated orifice in one by-pass and a larger calibrated orifice in 55 the other by-pass, means for connecting the supply chamber to the sight tubes through said conduit, and valve means associated with said discharge conduit and adjustable to one position to effect a flow of fuel through one by-pass into its tube and from that tube through said conduit and adjustable to another position to effect a flow of fuel through the other by-pass into its tube and from this second tube through said conduit, whereby fuel is admitted to one tube through said 60

75 conduit while it is being discharged from the other tube.

3. A device for testing carburetors, comprising in combination, a pair of sight tubes each provided with graduations for indicating the rate of fuel consumption, a constant level supply chamber having a pipe leading to the lower portion of each tube, a second connection including a calibrated orifice between said pipe and each tube, whereby two means are provided for filling each 10 tube one through said orifice and the other more rapidly, a conduit for delivering the fuel from the sight tubes to the carburetor, and valve means for placing either tube in operation to test the carburetor and operable also to control the means 15 for rapidly filling the tube.

4. A device for testing carburetors, comprising in combination, a casing having a front wall, a pair of sight tubes mounted upon said wall and provided with graduations for indicating the rate 20 of fuel consumption, a constant level supply chamber mounted within the casing, a discharge conduit connected to the two tubes, means for connecting said discharge conduit to a carburetor, means for connecting said chamber to each tube 25 through said conduit, a by-pass provided with a calibrated aperture for supplying fuel from said chamber to one tube and a by-pass provided with a larger calibrated aperture for supplying fuel from said chamber to the other tube, and a valve 30 associated with said conduit and operable to place one tube or the other in operation to determine the rate of fuel consumption and operable also to rapidly fill the other tube through said conduit.

5. A device for testing carburetors, comprising 35 in combination, a pair of sight tubes each provided with graduations for indicating the rate of fuel consumption, a constant level supply chamber, means for connecting said chamber to the two tubes, calibrated orifices provided in the connections leading from the supply chamber to each tube, a common discharge pipe for the two tubes, means for connecting said discharge pipe to a carburetor, conduits connected to said supply chamber and leading from each sight tube to said 45 discharge pipe, and a control valve associated with said conduits and constructed and arranged to control the flow therethrough into each tube and discharge therefrom, to thereby selectively place either one of the tubes in operation to test the 50 carburetor while the other tube is supplied with fuel from said chamber through its said conduit.

6. A device for determining the rate at which fuel is consumed by an internal combustion engine, comprising in combination, a pair of sight 55 tubes, a constant level supply chamber, means for connecting said chamber to the two tubes, a calibrated orifice provided in said connection between the supply chamber and one tube and a larger calibrated orifice provided in the connection between 60 the supply chamber and the other tube, a common discharge pipe for the two tubes, means for connecting said discharge pipe to the engine to be tested, conduits connected to said supply chamber and leading from each sight tube to said discharge 65 pipe, and a control valve associated with said conduits and constructed and arranged to control the flow therethrough into each tube and discharge therefrom, to thereby selectively place either one of the tubes in operation to test the engine while 70 the other tube is supplied with fuel from the supply chamber through its said conduit.

7. A device for determining the rate at which fuel is consumed by an internal combustion engine, comprising in combination, a pair of sight 75

tubes, a constant level supply chamber, a conduit connected to said chamber and to the lower portion of said tubes and having a discharge pipe through which either tube may discharge, means 5 for connecting said discharge pipe to the engine to be tested, a control valve associated with said conduit and discharge pipe and constructed and arranged to control the flow therethrough to each

tube and the discharge from each tube through said pipe, to thereby selectively place either tube in operation to test the engine while the other tube is supplied with fuel from the chamber through said conduit, a by-pass between each tube and said conduit, and a calibrated orifice in each by-pass. 5

HOWARD D. GREEN.
